UNITED STATES PATENT OFFICE.

ALBERT E. EVANS, OF YAKIMA, WASHINGTON.

NEST.

Application filed July 16, 1927. Serial No. 206,270.

This invention relates to a hen's nest, and more particularly to a novel construction of means for associating a curtain with the entrance opening of the nest, to permit the curtain to be used in various ways for various purposes namely as a curtain for said opening, or for the purpose of converting the ordinary nest into a trap nest when so desired.

10 More specifically stated, the invention contemplates the use of means including a curtain which is capable of being supported in one position for use as a curtain, and also capable of being automatically locked in a certain position to convert the ordinary nest into a trap nest, while furthermore, the curtain can be arranged and folded to occupy an inactive position.

20 The nature and advantages of the invention will be better understood when the following detailed description is read in connection with the accompanying drawings, the invention residing in the construction, combination and arrangement of parts as claimed.

25 In the drawings forming part of this application, like numerals of reference indicate similar parts in the several views, and wherein:—

30 Figure 1 is a view looking within the nest through the entrance opening, and showing the invention associated therewith.

35 Figure 2 is a view looking from the outside of the nest showing how the curtain is supported in a folded and inactive position.

40 Figure 3 is a view showing how the curtain is used to cover the entrance opening and capable of being adjusted to various lengths.

45 Figure 4 is a view illustrating how the curtain is initially arranged when it is adapted to be used in order to convert the ordinary nest into a trap nest, and also showing how the curtain is partially lifted by the hen entering the nest.

50 Figure 5 is a view showing how the curtain is locked in a given position to convert the nest into a trap nest, and

55 Figure 6 is a detail view of the curtain.

Referring to the drawings in detail, 10 indicates a portion of a nest of ordinary construction, and which portion is provided with an entrance opening 11. As above stated, the present invention is in the nature of an attachment for an ordinary nest, and capable of being associated with the latter,

so that it can be used in various ways to be hereinafter described.

The invention essentially embodies a pair of brackets 12, arranged along the side edges 60 of the entrance opening 11 adjacent the top thereof as clearly illustrated in Figures 1, 2 and 3. Each bracket is suitably secured to its adjacent edge and is formed at its upper end to provide a vertical extension 13 provided with a horizontal slot 14.

The curtain above referred to is indicated at 15 and clearly illustrated in Figure 6, one end of said curtain being folded upon itself to provide a hem to accommodate the rod 16, the latter having its ends offset at a right angle and terminating to provide hooks 17 for a purpose to be hereinafter described. Forming part of this curtain is a metallic plate 18 which may be of any suitable size, preferably slightly less than one-half of the area of the curtain. One edge of this plate is rolled upon itself as at 19 to form a clamp, which receives the adjacent edge of the curtain 15 and also a transverse 75 rod 20. The plate 19 is not otherwise attached to the curtain 15 permanently, but use is made of a slide 21 designed to embrace the opposed longitudinal edges of both the curtain 15 and the plate 18 so that by adjusting the slide along the edges of the plate 18, the length of the curtain may be varied when it is used in a manner illustrated in Figure 3. The plate is also provided with openings 22 adjacent the corners thereof 90 which openings are adapted to receive the extensions 13 of the brackets 12 when the curtain is used as illustrated in Figure 3.

We will first consider how the curtain is supported in an inactive position, and consequently when use of the curtain is not desired, the metallic plate 18 is arranged as illustrated in Figure 2, so that openings 22 will receive the extension 13 of the brackets 12, which support the plate in the manner 100 illustrated. The slide 21 is then moved in the direction of one end of the plate, thereby freeing the curtain 15 from the plate so that the curtain can be folded about the latter to bring the hooks 17 in a position to also engage the bracket extensions and be received by the horizontal slots 14. If it is desired to use the nest as an ordinary or open nest, the attachment is allowed to remain in the position just described, but if it is desired 110 to simply cover the entrance opening by means of the curtain, so as to darken the

nest, and also conceal the occupant of the nest from view, the parts are arranged as illustrated in Figure 3. For this purpose it is only necessary to disengage the hooks 17 from the bracket extensions 13, and allow the curtain 15 to depend from the plate 18 across the entrance opening as shown in Figure 3. It is manifest that by adjusting the slide 21 along the plate 18, the length 10 of the curtain 15 can be regulated according to the size of the entrance opening.

In order that the curtain may be used to convert an ordinary nest into a trap nest I employ in connection with the curtain above 15 described, a pair of bracket plates 23 which are secured to the edges of the entrance opening adjacent the lower end thereof as clearly illustrated.

Each of the bracket plates is formed from 20 a single piece of material folded upon itself and attached to the edge of said opening in any suitable manner. The brackets are preferably constructed to provide an inclined outer edge, the brackets themselves projecting 25 outwardly from the nest. Carried by each bracket is a slide plate 24 provided with a lug extension adapted to project a slight distance above the bracket plates 23, and any suitable means being employed for holding the plates 24 fixed with relation to their brackets in a given position. Pivoted within 30 each bracket 23 adjacent the lower end thereof is a plate 26 used in the capacity of a catch in the manner to be hereinafter described, the pivot for the catch being indicated at 27 while the catch is also provided with an arcuate shaped slot 28.

The slot 28 of each catch receives a stationary pin 29 to limit the movement of the 40 catch in either direction as clearly illustrated in Figure 5.

Now, when it is desired to convert the ordinary nest into a trap nest in accordance with the present invention, the metallic plate 45 18 above referred to is separated from the bracket extensions 13, and the curtain reversed so that the hooks 17 can be associated with said bracket extensions and received by the horizontal slots 14 thereof. The metallic plate is then arranged upon the upper edges 50 of the brackets 23 at an angle thereto, the lug extensions 25 of the plates 24 being arranged in advance of the transverse rod 20 which projects beyond the closed sides of the 55 curtain as clearly illustrated in Figure 6. When the curtain is mounted upon the nest in the manner above described, the parts are arranged as illustrated in Figure 4, so that when the hen enters the nest, the plate 18 is 60 engaged by the back of the hen and is therefore lifted off of the lugs 25 to the dotted line position as shown in Figure 4. As the hen passes through the entrance opening, the plate 18 is moved to the dotted line position 65 shown in Figure 4, so that after the hen

enters the nest, the plate 18 strikes the inclined edges of the bracket 23, moving downwardly over said bracket until the rod 20 passes beneath the lower edges of the bracket as will be readily understood. Then as the 70 curtain moves in the direction of the wall or partition 10, the projecting portions of the rod 20 strike the catches 26 moving them upwardly within the brackets until the lower edge or rod 20 of the curtain rests against 75 the wall or partition 10, then these catches 26 slightly gravitate in advance of the rod 20 to lock the curtain 20 in the position illustrated in Figure 5. The hen is then 80 trapped in the nest, and other hens excluded, by reason of the fact that the curtain is locked in the position just described, it being necessary in order to release the curtain, to elevate the catches 26 to allow the rod 20 to pass beneath the catches, whereupon the curtain 85 can be used in any of the various ways above described.

While it is believed that from the foregoing description, the nature and advantages of the invention will be readily apparent, I 90 desire to have it understood that I do not limit myself to what is herein shown and described, and that such changes may be resorted to when desired as fall within the scope of what is claimed. 95

What I claim is:—

1. A nest attachment comprising a curtain including a metallic plate secured to one edge of the curtain and arranged at one side thereof, said curtain being adapted to be arranged over the entrance opening of the nest, means for supporting the plate obliquely from the upper portion of the opening, with the curtain depending therefrom, and means for supporting the curtain from 105 the upper edge of the opening, with said plate substantially parallel with the curtain.

2. The combination with a nest having an entrance opening, of a curtain including a flexible portion, and a metallic plate secured to one edge of the curtain and arranged at one side thereof, means for supporting the plate obliquely with respect to said opening, adjacent the upper edge thereof, with the curtain depending from said plate, 110 means for adjustably connecting the curtain with the plate, whereby the length of the curtain may be varied with the plate disposed in the manner stated, and means for supporting the other end of the curtain 120 from the upper portion of the entrance opening with said plate arranged substantially parallel therewith.

3. The combination with a nest having an entrance opening, of a curtain including a 125 flexible portion, and a metallic plate secured to one edge of the curtain arranged at one side thereof, brackets secured to the opposed sides of said entrance opening, means whereby said plate may be supported from 130

the bracket obliquely thereto, a slide embracing the plate and curtain whereby the length of the curtain depending from the plate when obliquely disposed may be varied, and 5 means carried by the opposed edge of the curtain for association with the bracket, whereby the curtain may be arranged substantially over said opening with the plate arranged parallel with said opening.

10 4. The combination with a nest having an entrance opening, of a pair of brackets secured to the opposed side edges of said opening, a curtain including a flexible portion, a metallic plate secured to the lower edge 15 of the curtain and arranged at one side thereof and an adjustable slide embracing the plate and said curtain, means for supporting the plate from the bracket obliquely to said opening, this curtain being adapted 20 to be folded over said plate, means carried by one end of the curtain for engagement with said bracket when the curtain is folded as described, and said last named described means supporting the curtain upon 25 the bracket, to cover said opening with said plate arranged parallel with said curtain.

5. The combination with a nest having an entrance opening, brackets secured to the opposed edges of said opening, a curtain including a flexible portion adapted to be suspended from said brackets, and a metallic plate secured to the lower edge of the curtain, and arranged at one side thereof, ad-

ditional brackets projecting forwardly from the edges of said opening and upon which 35 said plate is normally supported in a position to be engaged by and lifted from the brackets as the hen passes through the opening, said plate subsequently gravitating to fully cover said opening, and cooperating 40 means carried by the last mentioned brackets, and said plate for automatically locking the plate in its last mentioned position.

6. The combination with a nest having an 45 entrance opening, of brackets secured to the opposed side edges thereof, a curtain including a flexible portion adapted to be suspended from said brackets, and a metallic plate secured to the lower edge of the 50 curtain and arranged at one side thereof, additional brackets projecting forwardly of the edges of said opening and upon which said plate is normally supported obliquely 55 and adapted to be engaged and removed from said brackets by the hen entering said nest, said plate subsequently gravitating to a lowered position to completely cover said opening, pivoted catches carried by the second mentioned brackets, and a rod arranged 60 transversely of said plate to cooperate with said catches, whereby the curtain is automatically locked in position to convert the ordinary nest into a trap nest.

In testimony whereof I affix my signature.
ALBERT E. EVANS.
